UNITED STATES PATENT OFFICE.

JOHN WALKER, JR., OF LONDON, ENGLAND.

COVER FOR LOOSE-LEAF BOOKS, FILES, AND TEMPORARY BINDERS.

1,001,483.

Specification of Letters Patent. Patented Aug. 22, 1911.

Application filed June 7, 1909. Serial No. 500,564.

To all whom it may concern:

Be it known that I, JOHN WALKER, JR., of Farringdon House, Warwick Lane, in the city of London, England, manufacturer, have invented certain new and useful Improvements in and Relating to Covers for Loose-Leaf Books, Files, and Temporary Binders, of which the following is a specification.

10 This invention relates to covers for loose leaf books, files and temporary binders and the like and has for its object to provide a cover which will lie flat on the table when opened and in use.

15 This invention may be applied to various forms of binding devices, and comprises a cover provided with two parallel folds spaced apart a distance equal to the thickness of the binding device or book and 20 means for attaching the cover to the binding device along one edge of the said binding device at or near one crease in the cover.

25 Figure 1 is a part plan and Fig. 2 is a section on line A—A Fig. 1 of one form of cover formed and attached to a binding device in accordance with this invention.

30 *a* is a cover provided with two parallel folds or creases *b* *b*, *c* is a binding device in which the leaves *d* are adapted to be filed. The binding device is preferably of the construction shown comprising a strip of material having longitudinal folds therein spaced apart substantially the same as the folds in the cover, the leaves being fastened 35 between the folded sides thereof. One face of the binding device is attached to the cover by a strip *e* or strips of canvas or other material, so that the edge *f* of the binding device is at or near one of the folds 40 in the cover.

In use the cover will lie open flat as shown

in Fig. 2 and the file can be opened or closed while the cover is in this position.

What I claim and desire to secure by Letters Patent is:—

1. In a device of the character described, 45 the combination of a cover having two folds spaced apart from each other, an attaching strip and a binding device for leaves attached to said attaching strip and disconnected from other parts of the combination, whereby said cover may lie flat when opened and the leaves may be turned without lifting said cover, said attaching strip being of flexible material and extending 50 outwardly along one of the folds in said cover, and having portions attached to said cover on either side of the said fold in said cover.

2. In a device of the character described, 60 the combination of a cover having two folds spaced apart from each other, an attaching strip and a binding device for leaves comprising a strip of material having two 65 bends therein spaced apart substantially the same as the folds in said cover, attached to said attaching strip and disconnected from the other parts of the combination, whereby said cover may lie flat when opened and the leaves may be turned without lifting said cover, said attaching strip being of flexible material and extending outwardly along one of the folds in said cover, and having portions attached to said cover on either side of the said fold in said cover. 70

75 In witness whereof, I have hereunto signed my name in the presence of two subscribing witnesses.

JOHN WALKER, JUNIOR.
